UNITED STATES PATENT OFFICE.

GUSTAV DE GRAHL, OF ZEHLENDORF, NEAR BERLIN, GERMANY.

BOILER-FURNACE.

1,073,039.

Specification of Letters Patent.

Patented Sept. 9, 1913

Application filed November 20, 1911. Serial No. 661,352.

To all whom it may concern:

Be it known that I, GUSTAV DE GRAHL, a subject of the German Emperor, and residing at Zehlendorf, near Berlin, Germany, have invented a certain new and useful Improvement in Boiler-Furnaces, of which the following is a specification.

My invention relates to methods of automatically admitting over-grate blasts into fire-boxes, and to apparatus for carrying the same into practice.

When overgrate blast was admitted into the fire-box heretofore, it was frequently difficult for the undergrate blast to pass through the grate, this being due, for example, to the grate having been charged too thickly or to low-grade coal. In all cases when the passage of the undergrate blast through the grate is impeded, the admission 20 of the overgrate blast, on the contrary, is accelerated while being drawn in, so that the conditions are such as to favor the cooling of the fuel on the grate and the formation of "dead" places, that is places where the 25 fuel is not properly burnt through.

A primary object of my invention is to obviate this defect. To this end I provide that the section of the passage admitting the overgrate blast is automatically reduced both 30 in proportion as the passage of the undergrate blast through the grate is rendered difficult during the main blast and as the velocity of admission of the overgrate blast into the fire-box is consequently increased, 35 and also according to the initial velocity of the overgrate blast.

By restricting the passage for the overgrate blast the conditions are rendered favorable for drawing the undergrate blast 40 through the grate. Consequently, the object of my method is automatically to restrict the admission of the overgrate blast or to cut it off completely as soon as it detrimentally affects the process of combustion and thus 45 favorably to influence the passage of the undergrate blast through the grate.

The apparatus substantially consists in the conduit which not only admits the supplementary air or overgrate blast and opens 50 into the fire-box, but is also provided with a valve opening inward being so constructed, for example, by the addition of a projection, rib or the like, that the valve constricts the free section of the passage for the supplementary air as it opens beyond a certain 55

amount and approaches the limit of its travel.

In order to vary the restriction of the passage to suit the coal burned at any time and, particularly, to prevent the passage for 60 the overgrate blast being restricted too much when the coal develops a great deal of smoke, I provide an adjustable stop for the valve. The valve may, for example, be so adjusted that when using steam coal the passage for 65 the overgrate blast is almost completely closed owing to the velocity at which said blast enters, whereas for coal developing much soot it is only slightly restricted or not at all.

One form of apparatus according to my invention is represented by way of example in the accompanying drawings, wherein:

Figure 1 is a front elevation of a fire-door frame having an inwardly opening fire-door, 75 Fig. 2 a front elevation, partly in section, enlarged, showing a portion of the fire-door frame, and Fig. 3 is a horizontal section on the bent line A—B in Fig. 2.

Referring to the drawing, 1 designates the 80 door frame provided with two lateral air-conduits 2, 3. Each of these has an enlargement 4, 5 respectively, which is separated by a projection or rib 6, 7 from the upper portion of the air-conduit. In each of said 85 lateral air-conduits there is an air valve 8, 9 mounted on a pivot 10, 11, respectively. On the wall of each lateral air-conduit is fixed a segment 12, 13, connected by arms 14, 15 with a sleeve 16, 17. Each of the latter extends through the wall of the lateral air-conduits 2, 3 above the valves and serves for the reception of a revolute pivot 18 which carries on the end projecting into the lateral air-conduit a lever 19 acting as 95 a stop for the valves, and on the other end a lever 20. Each lever 20 carries a handle 21 having a recess 22 (Fig. 3). The spring 23 in each recess 22 acts against the head 24 of the pointed pin 25. The pins are displaceably mounted in the handles 21 and are provided with nuts 26.

The segments 12, 13 each possess a series of notches or holes 27, 28 in which the pointed ends of the heads 24 can rest. The 105 levers 19, 19 are provided with springs 29, 30 which serve as resilient stops for the valves 8, 9. The position of each lever 20 with regard to the valves 8, 9 is such that as soon as the head 24 engages in the lower- 110

most hole 27 or 28, the lever 19 forming the stop for the valve allows the valve to open a minimum amount, just sufficient to cool the furnace front. After steam has been 5 shut off from the engine and after the main blast has ceased, the resilient stops for the valves 8, 9 are adjusted according as the auxiliary blast is set more or less in action, the arrangement being such that even when 10 the valves have opened a comparatively small amount there is a comparatively large opening for the overgrate blast passing through the air-conduits. If, after the auxiliary blast is shut off the main blast is 15 started, in case the passage of the undergrate blast through the grate is rendered difficult in consequence, for example, of the grate being too heavily charged and the velocity of the overgrate blast passing 20 through the air-conduits 2, 3 is consequently increased, the valves are raised still further owing to the high velocity of the air and approach so close to the ribs 6, 7 that the passage for the overgrate blast is correspondingly restricted. Owing to the admission 25 of the overgrate blast being impeded more undergrate blast is drawn through the grate during the main blast, so that the combustion is suitably regulated. The same action 30 takes place when "dead" places begin to appear on the grate, their appearance being always a proof that insufficient undergrate air is passing through the grate into the space above the grate. In this case 35 again, in consequence of the great velocity of the overgrate blast passing through the air-conduits 2, 3, the air-valves 8, 9 automatically adjust themselves in such manner that the admission of overgrate blast is im- 40 peded and consequently the passage of undergrate blast through the grate favored. Should the one side of the grate be more choked or stopped up than the other, so that overgrate blast is drawn in to an increased 45 extent at this choked up side and combustion consequently takes place more slowly at said side, the automatic regulating action described above will take place only in the case of that valve which is situated at said 50 side of the furnace.

For short flaming coal which tends to develop smoke only slightly, it is preferable to set the levers 19 provided with the stops for the valves in such a manner that the 55 valves occupy the upper position indicated in Fig. 2 as soon as they bear against the resilient stops. In this case the passage for the overgrate blast is materially restricted. In proportion as the coal tends to develop 60 soot such a position should be given to the lever 19 that the restriction is less. The

above described device is thus such that, after the levers 19 have been suitably set for each kind of coal, it enables the passage for the overgrate blast to be adjusted automatically.

I claim:

1. Apparatus for automatically controlling the admission of overgrate blast into the fire box of the furnace, comprising in combination, a suction conduit for the overgrate blast open at one end to the outer atmosphere and at the other end to the fire box, said conduit being provided with an internal rib extending through the suction and being immovable in the same, thus narrowing the said conduit, and a valve in said conduit opening toward the fire box adapted to approach said rib and restrict the passage for the overgrate blast, and an adjustable stop for said valve.

2. Apparatus for automatically controlling the admission of overgrate blast into the fire box of the furnace, comprising in combination, a suction conduit for the overgrate blast open at one end to the outer atmosphere and at the other end to the fire box, said conduit being provided with an internal rib extending through the suction conduit and being immovable in the same, thus narrowing the said conduit, and a valve in said conduit opening toward the fire box adapted to approach said rib and restrict the passage for the overgrate blast, and an adjustable resilient stop for said valve.

3. Apparatus for automatically controlling the admission of overgrate blast into the fire box of a furnace, comprising in combination, a suction conduit for the overgrate blast open at one end to the outer atmosphere and at the other end to the fire box, said conduit being provided with an inwardly projecting rib, a chamber between said rib and the atmosphere, a pivoted valve mounted in said conduit on the atmosphere side of said chamber, said valve being adapted to close said conduit when no air is passing therethrough and to swing through said chamber toward said rib under the influence of an increasing suction whereby said conduit is first opened and then restricted as the valve moves toward said rib, and an adjustable stop for limiting the movement of said valve toward said rib.

In testimony whereof, I affix my signature in the presence of two witnesses.

GUSTAV DE GRAHL.
